United States Patent Office

Des. 192,325
Patented Mar. 6, 1962

192,325

BOOK READING STAND

Arthur F. Johnson, Northbrook, Ill., assignor to Commerce Clearing House, Inc., Chicago, Ill., a corporation of Delaware

Filed Apr. 19, 1961, Ser. No. 64,817

Term of patent 14 years

(Cl. D33—3)

I claim:

The ornamental design for a book reading stand, as shown.
